HYDROSTATIC MECHANICAL LUBRICATOR

Kosciusko M. Anderson, Sweetwater, Tex.

Application October 7, 1941, Serial No. 413,950

7 Claims. (Cl. 184—27)

This invention relates to mechanical force-feed lubricators, and particularly to such lubricators as are adapted for lubricating the steam chests of locomotives, and other similar mechanisms.

The lubricator, in accordance with one embodiment of this invention, may employ hydrostatic pressure to feed the supply of lubricant to the forcing cylinders for distribution to the points to be lubricated, or, in another embodiment, may employ gravity feed to supply lubricant to the forcing cylinders.

A principal object of this invention is to provide a form of lubricator which is much simpler in construction, and is less subject to the various difficulties frequently experienced with other lubricators heretofore used.

Another important object is the provision of individual lubricant-forcing units, which are fully self-contained in all their essential working parts, and which are simply and easily removable bodily from the lubricator housing for replacement or repair, with a minimum amount of disruption of the operation of the other lubricant forcing units, where a plurality of such units are mounted in a common housing.

Other objects include the provision of simplified means for adjusting the displacement of the lubricant-forcing pistons, and for automatically locking the pistons in their adjusted positions, without removal of the forcing units from the lubricator housing.

Other and more specific objects and advantages of this invention will become apparent from the following detailed description when read in conjunction with the accompanying drawings, which illustrate one embodiment in accordance with this invention. It will be understood that various changes may be made in the details of this invention within the scope of the appended claims but without departing from the spirit of this invention.

In the drawings:

Fig. 1 is a longitudinal generally sectional view of the lubricator of this invention, having some of the internal parts cut away for purposes of better illustration;

Fig. 2 is a cross sectional view of the lubricator taken along line 2—2 of Fig. 1;

Fig. 3 is a transverse cross sectional view taken along line 3—3 of Fig. 2 to better illustrate certain of the details of the lubricator; and

Fig. 4 is a cross sectional view of another embodiment of a lubricator in accordance with this invention.

Referring to the drawings, particularly to Figs. 55

1 to 3 inclusive, the lubricator includes a box-like container 1 adapted to contain a supply of lubricating oil. The container is preferably constructed of metal of sufficient strength to withstand substantial internal pressures. A filler opening, closed by a screw plug 3, is provided in the top of the container for supplying lubricating oil thereto, and a screwed connection 4 is provided near the bottom of the container for the admission thereto of a suitable hydrostatic pressure fluid, such as steam condensate, which is supplied through a pipe 5 connected to a connection 4. A valved drain plug 6 is connected into the bottom of the container for emptying the same when desired, and a sight glass 7 is provided at one end of the container near the top thereof for showing the level of lubricating oil in the container. A plurality of openings 8, each provided with an annular packing shoulder 9 adjacent its upper edge, are provided in the top of the container. The openings 8 are arranged in longitudinal alignment and spaced from each other.

A plurality of individual lubricant-forcing units, each designated generally by the numeral 10, extend vertically through the openings 8 into the interior of the container. Since the units 10 are identical in construction, the following detailed description of one of these units will be understood to be applicable to all. These units comprise a generally cylindrical body having an upper discharge head 11 of relatively large diameter, which extends above the top of container 1, and a cylinder body 12 of reduced diameter 35 extending below the top of the container into the interior thereof. A flange 13 extends laterally about the base of head 11 and provides means for rigidly fastening the unit to the top of the container by means of cap screws 14. Just beneath flange 13, an annular shoulder 15 is provided about the upper end of cylinder body 12 which is generally complementary to packing shoulder 9, and a ring gasket 16 is interposed between the shoulders 9 and 15 to tightly seal opening 8 45 when the unit 10 is fastened in place therein by tightening down the cap screws 14. Discharge head 11 has an axial bore 17, threaded internally at 18, at its upper end and terminating at its lower end in a tapered annular valve seat 19 50 which surrounds the upper edge of an axial passageway 20 of smaller diameter than bore 17. A ball check valve 21 is disposed in bore 17, cooperating with valve seat 19 to open and close passageway 20. A valve spring 22 is also disposed in bore 17 in contact with check valve 21 and acts

to normally hold check valve 21 on seat 19 under pressure applied by means for a threaded spring follower 23 which is screwed into the upper end of bore 17 by engagement with threads 18, and which serves also to plug the top of bore 17. A passageway 24, communicating with bore 17, extends laterally through the side of head 11 and has connected thereto a lubricant discharge pipe 25 which leads to the point to be lubricated by the unit 10. Passageway 20, bore 17 and passageway 24, constitute the discharge passageway for the unit.

The cylinder body 12 is also bored axially to provide a cylinder 26 for the reception of a lubricant-forcing piston 27, the cylinder 26 tapering at its upper end and communicating with the lower end of the restricted passageway 20. An intake port 28 extends laterally through cylinder body 12 at a point adjacent the top of the container and provides communication between cylinder 26 and the upper portion of container 1. The lower end 12a of cylinder body 12 is further reduced in external diameter to provide an annular shoulder 29. The upper end portion of piston 27 is reduced in diameter to form a boss 30 which is provided with a diametric slot 31 in its upper surface for engagement by a suitable adjusting tool, in a manner and for a purpose to be more fully explained hereinafter. The lower end of piston 27, which extends below body 12, is threaded externally at 32 and threadedly attached thereto is a cam follower 33 having an internally threaded socket 37 for the reception of the threaded end of piston 27. Cam follower 33 is provided on its upper face with a short annular boss 34. A coil spring 35 surrounds the exposed portion of piston 27 extending between the lower end of body 12 and the upper face of cam follower 33. The upper end of spring 35 surrounds the lower end portion 12a and seats against the shoulder 29, while the lower end of spring 35 surrounds boss 34 and seats against the upper face of cam follower 33, and in this arrangement, is held under compression so as to normally thrust cam follower 33 downwardly and thereby pull piston 27 downwardly in cylinder 26.

An opening 36 (Fig. 3) is bored horizontally through the body of cam follower 33 into communication with the internally threaded socket 37 in which the threaded lower end of piston 27 is received. The inner end of opening 36 is slightly restricted to form a seat for a steel locking ball 38 which is disposed in bore 36 so as to normally protrude slightly into socket 37. Ball 38 is yieldably held in this position by means of a coil spring 39 mounted in the outer end of opening 36, and is held pressed against ball 38 by means of a pin 41, which is inserted in the transverse hole 42 drilled at right angles to the hole 36 through the cam follower 33. The threads 32 on the lower end of piston 27 are provided with a number of longitudinal slots 43 into which the portion of ball 38 protruding into socket 37 will be pressed when these slots come into registration with the inner end of opening 36. The engagement of ball 38 with the slots 43 acts to lock piston 27 against undesired rotation in socket 37, such as may tend to occur as a result of vibration during reciprocation of the piston. Of course, when positive rotative pressure is applied to turn piston 27, the ball 38 will be forced outwardly in opening 36 against the pressure of spring 39, permitting the piston to turn in the threads of socket 37 until the next slot 43 comes into registration with the ball. A flat guide mem-

ber 44, for guiding the cam follower 33 during its reciprocation, is rigidly attached at one side to cylinder body 12 and extends downwardly parallel to piston 27 and terminates at its lower end in an under-turned lip 45 which extends under the adjacent bottom edge of cam follower 33, and which serves to prevent cam follower 33 and piston 27 from becoming disengaged from the cylinder 12 when removing pumping unit 10 from container 1, and serves also to stiffen and retain in their assembled relation all of the parts constituting the lubricant forcing unit 10.

Extending substantially centrally through the lower portion of container 1 from end-to-end thereof is a shaft 46 having a bearing 47 in one end of container 1, the opposite end of the shaft having a bearing 48 in the opposite end of the container and extending exteriorly thereof through a packed stuffing box 49. The outer end of shaft 46 carries a ratchet wheel 50 which is engaged by pawls 51 carried in a spider 52 which is attached to a pivoted driving member 53, which is in turn connected to some suitable reciprocating element of the machine to be lubricated (not shown) in a more or less conventional manner for driving the shaft 46 in an intermittent or step-by-step rotation. Obviously, shaft 46 may be otherwise intermittently or continuously rotated, such drives being more or less conventional for force-feed lubricators, and selection of a particular type of rotation of shaft 46 being largely dependent upon the service in which the lubricator is to be employed.

Shaft 46 carries a plurality of eccentric cams 54, one of which registers with each of the cam followers 33 of the several lubricant-forcing units 10. These cams 54 are preferably set at different angles so as to vary the relative timing of the strokes of the several forcing pistons, although it will be understood that all of the cams may be at the same angle, if it is desired to have all of the units discharge simultaneously. Cam followers 33 are, of course, normally held in yieldable contact with their corresponding cams 54 by the compressive action of springs 35.

A heating coil 55 extends into container 1 and is provided exteriorly of the container with an inlet connection 56 and an outlet connection 57 for circulation through coil 55 of a suitable heating fluid, such as steam, hot water, and the like, for maintaining the body of lubricant in the container in fluid state under low temperature conditions. Other conventional forms of heaters may, of course, be used in place of the specific form herein described.

In operation, when the lubricator is employed to lubricate the steam chest of a locomotive, for example, a supply of lubricating oil is introduced into container 1 through filler opening 2, which is then tightly closed by means of plug 3. Lubricant discharge pipes 25 are connected to the points to be lubricated and a supply of hydrostatic pressure fluid, such as steam condensate under the pressure of the steam chest to which the lubricant is to be forced, is admitted through pipe 5 into the lower portion of container 1, where it acts to float the body of lubricating oil to the upper portion of container 1. Sufficient hydrostatic fluid is thus continuously admitted to container 1 to at all times, maintain the level of lubricating oil in the container above the level of intake ports 28. Rotation of shaft 46, acting through the cams 54, produces the lubricant-forcing strokes of the pistons 27, which on the down stroke, as shown 75 in the center unit 10 in Fig. 1, draws the oil into

cylinder 26 through intake port 28, and on the up-stroke, as shown in the view of the right hand unit 10 in Fig. 1, forces the oil through passageway 20, check valve 21, bore 17, and thence through discharge passageway 24 into pipe 25, whence the lubricant is discharged to the point to which it is to be supplied.

By employing the described hydrostatic feed under substantially the same pressure against which the lubricant is discharged, the only pressure against which the forcing pistons 27 are required to work is the weight of check valve 21 and the compressive strength of spring 22, which is ordinarily made quite small, and the excess pressure is, therefore, substantially negligible in a lubricating system of the kind here described. This arrangement assures a continuous flow of lubricant through pipes 25, and the overhead feed eliminates the necessity for protective screens about suction ports 28 and assures a continuous supply of clean oil to the cylinders 26, since any sediment which may be present in the oil will ordinarily settle by gravity to the bottom of the container. If one of the discharge pipes 25 should break while the device is under hydrostatic pressure, then by means of the described construction and arrangement of the parts of each forcing unit, the excess of the hydrostatic pressure which would immediately develop within the container would force the cam follower 33 and piston 27 of that unit upward and force the piston past port 28, thus automatically closing off the supply of lubricating oil and effectively preventing further discharge of lubricant from that unit and would also prevent further operation of that unit, since spring 35 is not sufficiently strong to overcome the excess hydrostatic pressure developed.

Adjustment of the displacement of piston 27 in order to vary the quantities of oil discharged, is rendered quite simple and quick by the arrangement provided in accordance with this invention, without requiring the removal of the unit from the container. Screw plug 23 is removed from bore 17, spring 22 is also withdrawn, and ball valve 21 is extracted by means of a suitable tool, such as a magnetized screw driver, for example. A screw driver, or other suitable flat-edged tool, is then inserted through bore 17 and passageway 20 and engaged in slot 31 of the piston boss 30. The piston is then rotated thereby to screw it either up or down in socket 37 of cam follower 33, to thereby lengthen or shorten the movement of piston 27 above port 28 as desired. The torque thus applied to piston 27 is sufficient to turn the latter against the pressure applied to lock ball 38 by spring 39, the ball being thrust back into bore 36 while the turning of the piston takes place. When a sufficient number of turns has been made to produce the desired lengthening or shortening of the piston displacement, as the case may be, the nearest slot 43 is brought into registration with ball 38 which then thrusts into the slot and automatically locks the piston against any further rotative movement which may occur under operating conditions. Check valve 21, spring 22 and plug 23 are then replaced and the unit is ready for operation on the adjusted displacement, without having removed the unit 10 from the container.

An entire lubricant-forcing unit may be bodily removed for repair or replacement without disturbance of the other units, merely by removing the cap screws 14, and withdrawing the unit bodily from the container. If another unit is not immediately available for replacement, the opening 8 may be closed by a suitable cap and the lubricator

continued in operation with the remaining units at their full efficiency. With the form and arrangement of the individual units 10, in accordance with the embodiment herein described, it will be seen that each of the units 10 is entirely independent of the others, and failure of one in no way impairs or affects the efficiency or operability of the others. It will be understood that any desired number of lubricant forcing units 10 may be employed.

While the lubricator, above described, is adapted particularly for employment with hydrostatic feed of the lubricant to the forcing units, it will be evident that the lubricator may also be used with gravity feed, it being necessary only to turn the device through an angle of 180 degrees about shaft 46 to operate in this way, the functioning of the individual units 10 being in no way adversely affected by this change of position.

Fig. 4 illustrates another form of lubricator in accordance with this invention in that the container 58 is cylindrical in form, being preferably constructed of a length of pipe or tubing adapted to withstand relatively high internal pressures. In this case the lubricant forcing unit 10 is provided with a flange 59 which does not employ a shoulder 15, as in the previously described embodiment for sealing the unit in the container but rests directly on a flat seating surface 60 mounted on the exterior of container 58. A flat ring gasket 61 is interposed between flange 59 and seating surface 60 to seal the opening 62 in the top of the container. In all other respects, this modification is substantially identical with that previously described, the corresponding parts accordingly being designated by the same numerals. This embodiment shown in Fig. 4 functions, of course, in the same manner as that previously described.

Wha I claim and desire to secure by Letters Patent is:

1. A lubricator, having an oil reservoir, a lubricant forcing unit applicable to and removable bodily from said reservoir and comprising an elongated body extending into said reservoir, said body having an axial bore extending throughout its length, a discharge port communicating with one end of said axial bore exteriorly of said reservoir, the opposite end portion of said bore within said reservoir constituting the forcing cylinder, an intake port communicating with said cylinder interiorly of said reservoir and adjacent the wall thereof through which said body is inserted, check valve means disposed in said bore between said discharge and intake ports to control communication therebetween, a piston slidably positioned in the outer end of said cylinder, a cam follower threadedly engaging the outer end of said piston whereby longitudinal adjustment therebetween may be effected, and means carried by the inner end of said piston and engageable through said axial bore from the exterior thereof for effecting rotation of said piston relative to said cam follower, and means for imparting reciprocating movement to said piston.
2. A lubricator, having an oil reservoir, a lubricant forcing unit applicable to and removable bodily from said reservoir and comprising an elongated body extending into said reservoir, said body having an axial bore extending throughout its length, a discharge port communicating with one end of said axial bore exteriorly of said reservoir, the opposite end portion of said bore within said reservoir constituting the forcing cylinder, an intake port communicating with said cylinder interiorly of said reservoir and adjacent the wall

thereof through which said body is inserted, check valve means disposed in said bore between said discharge and intake ports to control communication therebetween, a piston slidably positioned in the outer end of said cylinder, a cam follower threadedly engaging the outer end of said piston whereby longitudinal adjustment therebetween may be effected, means carried by the inner end of said piston and engageable through said axial bore from the exterior thereof for effecting rotation of said piston relative to said cam follower, locking means carried by said follower and cooperating with the threaded portion of said piston for locking said piston to said follower, and means for imparting reciprocating movement to said piston.

3. A lubricator according to claim 1 wherein said forcing unit includes a flat guide member for said follower rigidly attached to said body extending parallel to said piston and having a portion cooperating with said follower to limit the outward movement thereof relative to said cylinder.

4. A lubricator according to claim 2 wherein said locking means carried by said cam follower includes a recess in said follower, a ball member yieldably seated in said recess and adapted to normally protrude therefrom into engagement with locking slots carried by said piston and disposed longitudinally of said threaded portion thereof.

5. A lubricator, having an oil reservoir with an opening in one wall thereof, a lubricant forcing unit applicable to and removable bodily from said reservoir through said opening and comprising an elongated body extending into said reservoir and having a flange enclosing said opening and furnishing means of attachment with said wall of the reservoir, said body having an axial bore extending throughout its length, a discharge port communicating with one end of said axial bore exteriorly of said reservoir, the opposite end portion of said bore within said reservoir constituting the forcing cylinder, an intake port communicating with said cylinder interiorly of said reservoir and adjacent the wall thereof through which said body is inserted, check valve means disposed in said bore between said discharge and intake ports to control communication therebetween, a piston slidably positioned in the outer end of said cylinder, a cam follower threadedly engaging the outer end of said piston whereby longitudinal adjustment therebetween may be effected, means carried by the inner end of said piston and engageable through said axial bore from the exterior thereof for effecting rotation of said piston relative to said cam follower, and means for imparting reciprocating movement to said piston.

6. A mechanical force feed lubricator of the type employing hydrostatic pressure feed of lubricating oil to the lubricant forcing units and having an oil reservoir, means for supplying lubricating oil to said reservoir, means for supplying hydrostatic fluid under pressure into the lower portion of said reservoir, a plurality of independent unitary lubricant forcing units applicable to and removable bodily from said reservoir through the top thereof, each of said units comprising an elongated body extending into said reservoir and having an axial bore extending throughout its length, a discharge port communicating with one end portion of said axial bore exteriorly of said reservoir, the opposite end portion of said bore within said reservoir constituting the forcing cylinder, an intake port communicating with said cylinder interiorly of said reservoir and closely adjacent the top thereof, check valve means disposed in said bore between said discharge and intake ports to control communication therebetween, a piston slidably positioned in the lower end of said cylinder, a cam follower threadedly engaging the lower end of said piston whereby longitudinal adjustment therebetween may be effected, means carried by the upper end of said piston and engageable through said axial bore from the exterior thereof for effecting rotation of said piston relative to said cam follower, and a shaft rotatably journaled in the lower portion of said reservoir and bearing a plurality of longitudinally spaced cams engaging the cam followers of said plurality of forcing units for imparting reciprocating movement to said pistons upon rotation of said shaft.

7. A lubricator, having an oil reservoir, a lubricant forcing unit applicable to and removable bodily from said reservoir and comprising an elongated body extending into said reservoir, said body having an axial bore extending throughout its length, a discharge port communicating with one end portion of said axial bore exteriorly of said reservoir, the opposite end portion of said bore within said reservoir constituting the forcing cylinder, an intake port communicating with said cylinder interiorly of said reservoir, check valve means disposed in said bore between said discharge and intake ports to control communication therebetween, a piston slidably positioned in said cylinder, a follower member adjustably engaging the outer end of said piston, means carried by the inner end of said piston and engageable through said axial bore from the exterior thereof for effecting longitudinal adjustment of said piston relative to said follower member, and means for imparting reciprocating movement to said piston.

KOSCIUSKO M. ANDERSON,
